(57) **CLAIM**

The ornamental design for a dosing cup as shown and described.

DESCRIPTION

FIG. 1 is a front perspective view of a dosing cup embodying our new design;

FIG. 2 is a front view of the dosing cup;

FIG. 3 is a left view of the dosing cup;

FIG. 4 is a back view of the dosing cup;

FIG. 5 is a right view of the dosing cup;

FIG. 6 is a top view of the dosing cup; and,

FIG. 7 is a bottom view of the dosing cup.

The broken lines in the figures show portions of the dosing cup that form no part of the claimed design.

1 Claim, 3 Drawing Sheets
